UNITED STATES PATENT OFFICE.

ELMER E. JOHNSON, OF HERKIMER, NEW YORK, ASSIGNOR OF ONE-HALF
TO JONAS H. AUSMAN, OF SAME PLACE.

TRACE-FASTENER.

SPECIFICATION forming part of Letters Patent No. 429,452, dated June 3, 1890.

Application filed March 5, 1889. Serial No. 301,878. (No model.)

To all whom it may concern:

Be it known that I, ELMER E. JOHNSON, of Herkimer, county of Herkimer, in the State of New York, a citizen of the United States, 5 have invented certain new and useful Improvements in Safety Trace-Fasteners, of which the following is a specification.

The invention relates to trace-fasteners.

The object of the present invention is to 10 produce a safety trace-fastener of simple and comparatively inexpensive construction and of great utility, adapted to be readily applicable to the ordinary form of whiffletrees or draft-bars regardless of the size of the same, 15 and yet obviate the necessity of cutting or tapering the same for the reception of the holder, and which will securely hold the trace or traces against accidental displacement or removal, and thereby insure positive safety.

20 The invention consists in the construction and novel combination and arrangement of parts, hereinafter fully described, illustrated in the accompanying drawings, and pointed out in the claim hereto appended.

25 In the drawings, Figure 1 is a plan view of an end of a whiffletree provided with a trace-fastener constructed in accordance with this invention, showing in dotted lines the position of the parts when receiving a trace. Fig. 30 2 is a side elevation, the trace being shown in dotted lines. Fig. 3 is a perspective view of the trace-holder detached.

Referring to the drawings, A designates an 35 end portion of a whiffletree or draft-bar of the ordinary construction, having its end adapted to be encompassed by the trace eye or slot in a trace.

B is a trace-holder, constructed of a single 40 piece of light steel bent at its middle to form a transverse elongated trace-receiving loop c^2 and parallel elongated and approximately L-shaped side arms C and C', arranged sufficiently far apart to admit readily between them at their pivotal point an ordinary whiff- 45 fletree, and capable of being spread to receive a larger whiffletree. The parallel side arms C and C' are respectively of approximately right- 50 angular form longitudinally, they being bent or curved, as at D, then diverged, and finally converged, forming a rear transversely-dis-

posed trace-receiving eye G, and the said side bars comprise straight portions E F, connected by the intervening curvilinear portion D, the rearwardly-inclined portion being preferably of not over half the length of the laterally- 55 extended portion.

In each side arm, at above or beyond the point D of bending of the arms, I form a perforation D', whereby, by means of a bolt or rivet D², I pivotally secure the respective side 60 arms at opposite sides of the end portions of the interposed whiffletree, likewise perforated for the bolt.

When I desire to attach a trace to an end of a whiffletree, I grasp the pivoted holder B, 65 swinging it inward and forward, as shown by dotted lines in Fig. 1, and then pass the end of the trace H through the eye C² thereof, and thence rearward until a trace eye or slot is in line with the end of the whiffletree when the 70 same is pressed into engagement, and strain upon the trace causes the lateral arms C and C' to swing backward adjacent to the whiffletree-face.

To remove the end of the trace from the 75 whiffletree, the aforesaid action is reversed, the arms C and C' being swung forward as before, whereby sufficient slack is obtained to admit of the easy removal of the trace-eye from its lodgment. 80

The eye G is of great service whenever, as it frequently occurs in the proper and satisfactory adjustment of the trace longitudinally, it is requisite that the second or some succeeding trace-eye should be secured to the 85 whiffletree end, in which case by means of my device the trace end usually extending some distance rearward beyond the whiffletree and presenting an appearance that is displeasing and ungraceful is entirely obviated, as the 90 extended end may readily be brought around alongside of the whiffletree and inserted through the eye G, thereby not only causing the same to present a neat appearance, but additionally the above arrangement serves 95 to more securely hold the trace-eye of the trace upon the whiffletree end, (if more positive hold be possible,) as the greater the longitudinal or lateral strain upon the trace the closer the contact of the eye C² to the whiffle- 100

tree, and thus in a corresponding degree will the socket portion G bear upon and hold the extended trace end lying therein.

It will be noticed that the arms C C' are arranged at such distance apart that they are adapted to receive a whiffletree of the narrowest construction, and that the two terminals of the arms meet at the center after forming the eye G. It will be evident by the construction described that the holder may be sprung apart and the space between its arms C C' widened to a distance adapted to receive whiffletrees of any ordinary width, the arms and their terminals being spread for that purpose. It will also be noticed that by pivoting the holder beyond the bent portions D, I am enabled to swing said holder open to a greater distance than if pivoted directly at the bend. Furthermore, I am thus enabled to dispose the arms C and C' parallel with the whiffletree, and thus the eye C² is directly in line with the trace, which fits the same somewhat closely. It is apparent that should I pivot the holder directly at the bend, as heretofore, the lateral swinging of the trace as caused by the movements of the horse would not be met by a corresponding swinging of the holder, and the result would be that the holder would soon become loose at its pivot and in a comparatively short time inefficient.

By pivoting the holder in the rear of the bend, and therefore in the rear of the eye C², any movement of the trace caused by the movement of the horse will be met with a corresponding movement of the holder at its free end, and the trace exerts no strain whatever upon the holder, which would not only tend to loosen the same, but unlock it and liberate the trace.

What I claim is—

The herein-described trace-holder, formed of a single piece of light metal and bent at its middle to form a transverse eye C², rearwardly bent to form opposite parallel arms approximately right angularly, as at D, and 45 perforated beyond said bent portion, as at D', in rear of the plane of the eye C², and diverged and converged meeting to form an eye G, closely fitting the trace, the arms being sprung apart to receive any size whiffletree, 50 substantially as described.

In witness whereof I have hereunto set my hand this 27th day of February, 1889.

ELMER E. JOHNSON. [L. S.]

In presence of—

A. J. SMITH,
W. C. PRESCOTT.
